MEANS FOR AND METHOD OF ELECTRICAL PRINTING

James K. Duncan, Chicago, Ill.

Application February 16, 1934, Serial No. 711,491
Renewed May 6, 1940

15 Claims.

(Cl. 204—2)

My invention relates in general to the art of printing and has more particular reference to means for and methods of producing prints electrically, the invention having special reference to the utilization of electrolytic action in printing.

An important object of the invention is to provide for printing by electrolytic action.

Another object is to provide for printing from a stencil by the action of electricity.

Another object is to provide a printing stencil particularly adapted for printing by electrical action; a further object being to provide a stencil from which prints may be produced and the stencil preserved as a permanent master record.

Another important object is to provide means operable in conjunction with a stencil to produce prints by electrical action.

Another object is to provide a printing stencil adapted to receive master impressions to be reproduced by printing and having means adapted for deposit, by electrolytic action, upon a surface to be printed during the printing operation.

Another object is to provide a printing stencil adapted to be impressed in accordance with design impressions to be reproduced and having current blocking means whereby to prevent current flow through the stencil save at the impressions so that the stencil may be used in printing by electrolytic action.

Another object is to provide a stencil having current-carrying portions and current-blocking portions adapted to be impressed with a design to be reproduced whereby the same may be utilized as a master form in printing by electrical action, that is to say, a stencil which may be used to produce a desired number of printed copies and which is of sufficiently permanent character permitting storage and subsequent reuse in producing additional printed copies at any time; a further object being to provide a master stencil which will produce prints all of which are of like quality and intensity throughout a large run of copies.

Another object is to provide a printing stencil which may be cut or impressed, either manually, in a typewriter, or in any other convenient manner without the use of special ribbon, a stencil which, after cutting, may be instantly visualized without difficulty and which does not contain smearable pigments capable of befouling the hands and clothes of an operator.

Another object is to provide a printing stencil of laminated construction whereby the strength of the stencil is improved, a further object being to form a stencil in which at least one of the

5 laminations comprises a layer of current-carrying material preferably a metal capable of being deposited electrolytically.

Another object is to provide apparatus for printing electrically, more particularly by electrolytic action and including means to mount a master form or stencil in printing position and for supplying electrical current to the mounted form in order to accomplish the printing operation when the form is impressed upon the surface of the sheet being printed; a further object being to provide a device capable of printing upon stock of any desired thickness.

Another object resides in providing an improved method of printing, which is as well suited to the long run or multi-copy print production as to the so-called "system" or short-run print production, in which a few prints only are made at a time, the cost of operation being within the requirements of the system or short-run field while the ability to furnish many hundreds of copies from a single master stencil renders the process suitable for the circular letter or multi-copy field.

Another object is to provide a process which is entirely clean, free from disagreeable odors, and free from messy pigments capable of soiling the hands and clothes of the printer, a further object being to provide a process in which the 10 printed copies are sharp and permanent, not affected by light, heat, moisture, or oil.

Another object is to provide an improved electrical printing process in which the electrical currents employed need not pass through the 15 sheets on which the printed copies are formed.

Another object is to provide a printing process in which separating sheets are not required between freshly made prints, the prints being unsmeearable at the conclusion of the printing operation and hence may be piled on top of each other immediately, a further object being to provide a printing process in which printing speed is limited only by the maximum speed limit of the mechanism utilized in carrying out the process.

Another object is to provide a printing process adapted to produce neat, sharp prints upon stock of any desired thickness and of any material capable of receiving printing.

Another object is to provide a printing process wherein the pigment is applied on the paper opposite the edges of a cut stencil employed in the printing process.

Another object is to provide for printing by the formation or deposition of pigment in a sur-

face to be printed opposite the edges of a perforation formed in a stencil sheet without making provision for blocking the deposition of pigment inwardly of said edges.

Another object is to provide for printing by deposition, in a surface to be printed, of pigment derived by the decomposition of a stencil or printing form and applied to the surface by means of electrical current flow.

Another object is to provide for printing by decomposition or other action in a substance carried in the body of the element being printed by action electrically induced therein.

Another object is to provide for selective color printing by varying the amount of current applied to the element being printed, or by reversing the flow of such current.

Numerous other objects, advantages, and inherent functions of the invention will become apparent to those familiar with the art of printing as the invention is more fully understood from the following description, which, taken in connection with the accompanying drawings, discloses an embodiment of the invention.

Referring to the drawings:

Figure 1 is a view showing printing apparatus embodying my present invention in side elevation;

Figure 2 is a view showing the apparatus illustrated in Figure 1 as viewed from above;

Figures 3 and 4 are sectional views taken substantially along the lines 3-3 and 4-4 in Figures 1 and 2 respectively;

Figure 5 is a sectional view taken substantially along the line 5-5 in Figure 2;

Figure 6 is a diagrammatic view illustrating electrical connections forming a part of the apparatus shown in Figures 1 and 2;

Figures 7 and 8 are diagrammatic views to illustrate my improved printing process, the same comprising highly magnified sectional views of sheets passing in contact with the printing form or master stencil during the printing operation;

Figure 9 is a face view of a stencil embodying my present invention and adapted for use in the apparatus shown in Figures 1 and 2; and

Figure 10 is a section taken along the line 10-10 in Figure 9.

To illustrate my invention, I have shown, on the drawings, apparatus for printing by electrical action, wherein the sheet to be treated is exposed to the action of electrical currents at the places where it is desired to print marks on the sheet, the apparatus including means for preventing exposure of the sheet to the action of the electrical currents at the places where no printing is desired. The apparatus illustrated is as well adapted for printing by electrolytic action, wherein the electrical currents deposit the pigment on the printed surface, as it is adapted for printing by electrolytic action, in which the sheet being printed is treated with suitable chemicals adapted to change color when exposed to the action of the electrical current.

While any suitable means for applying or exposing the sheet to be printed to the action of the electrical currents may be employed, I prefer to use and therefore have illustrated a master form arranged as a stencil 101 and adapted for removable mounting in the printing apparatus in position to accomplish the printing function. I find that the stencil type of printing form is well suited for my purpose in controlling the application of the electrical currents

to the sheet or surface to be printed. The stencil, in its simplest form, comprises a preferably laminated sheet including a layer of electrical conducting material 103. In addition, the stencil may be strengthened by including a layer of preferably fibrous material 105, such as paper, on a surface of which the conducting layer may be formed and insulating layers 107 and 109 of preferably non-conducting water-proof material are applied to the outer surfaces of the layers 103 and 105. The total thickness of the layers, forming the stencil, need not be in excess of .002 inch, for which reason the stencil is not unusually bulky and can be easily cut in a typewriter. At the same time, the sheet is sufficiently rigid and self-supporting not to require particularly careful handling and may be preserved as a permanent record after being cut.

20 The opposite end edges of the stencil are preferably provided with layers 111 of suitable protective material, such as wax or varnish, and carry spaced eyelets 113 preferably of metallic conducting material, which form electrical contact with the layer 103 and serve to bind the layers together. The fibrous material 105 is preferably paper formed with water-marks 211, which are visible through the layers 107 and 109, which is preferably formed of translucent material sufficiently transparent to permit the water marks to be seen therethrough. In this fashion, the stencil may be provided with guide lines to assist in the cutting thereof or the water marks may be formed in accordance with a preferred or suitable design in order to afford identifying means for the product.

25 The stencil is prepared for printing by impressing the same with a design to be reproduced, the design being cut into and through the metallic layer. The sheet to be printed is then pressed upon the cut stencil while electrical currents are passed through the metallic portions of the stencil and into the cut openings therein, means being provided to fill said openings with a preferably fluid current-carrying medium, through which the electric circuit is completed. As the currents pass into and through the cut portions of the stencil, they act upon the surfaces of the sheet being treated, which are exposed opposite 30 said cut portions. It is not necessary to cause the electrical currents to pass entirely through the sheet being printed and to return to the power source from the side of the sheet opposite that to which the stencil is applied; but the currents may be returned from the cut-out portions of the stencil to the power source by means of an electrical circuit-forming path disposed on the same side of the sheet being printed which is exposed to the stencil or printing element, this feature being of particular importance in my present invention, as will hereinafter more fully appear.

35 In order to most conveniently contact the sheet to be printed with the stencil and at the same time provide for the application of the electrical currents, I provide apparatus including a main frame 15, in which is mounted a stencil-carrying drum 17, means including a motor 19, and suitable transmission mechanism 21 for rotating the drum 17, a pressure roller 23, means comprising a carrier 25 for sheets to be printed, feed mechanism 27 actuated by the motor in timed relationship with the rotation of the drum 17 for feeding sheets from the carrier in succession between the drum and pressure roller, and a re-

ceiver 29 into which the printed sheets are delivered after contacting with the stencil-carrying drum.

The transmission 21 is driven by the motor 19 and is drivingly connected to rotate a worm 119, which, in turn, is drivingly associated with a worm wheel 123 fast on a shaft 65 on which the drum 17 is mounted for rotation in the frame 15. The worm 119 is splined upon and rotates with a shaft 121 forming a part of the transmission mechanism. The worm is normally urged on the shaft as by means of a spring 125 to a position in which it drivingly engages the worm wheel 123, but if, for any reason, the wheel should be prevented from turning, the continued rotation of the shaft 121 will cause the worm to travel axially on the shaft against the yielding resistance of the spring 125 to a position in which the worm no longer drivingly engages the wheel.

The shaft 65 is provided with a crank 127, in which is journaled an adjusting nut 129 carrying a fitting 131 which, by turning the nut 129, may be moved to alter the spacing between the fitting 131 and the axis of the shaft. The fitting 131 forms a wrist pin, to which one end of a connecting rod 133 is journaled. The other end of the connecting rod is connected to a cross-bar 135 extending above the sheet carrier 25. The bar 135 is journaled at its opposite ends in lever arms 137 pivoted in the frame 15 on opposite sides of the carrier 25. As the shaft 65 is turned by the motor 19 operating through the transmission 21, the connecting rod 133 will be reciprocated to cause the bar 135 to swing back and forth above the sheets in the carrier 25, the bar traveling an arcuate path, the center of which coincides with the pivoted axis of the levers 137. The bar 135 has a fitting 139 fixed thereon, which fitting carries an adjustable stop 141 in position to overlie a seat 143 formed in the arm 133. The stop 141 is adjusted to cause the seat 143 to engage the stop 141 during the travel of the rod in one direction, that is to say, toward the left, viewing Figure 1, and to disengage the stop during the travel of the connecting rod in the reverse direction. This movement causes the slight angular rotation of the rod 135 in a counter-clockwise direction viewing Figure 1 during the movement of the rod toward the left. The rod is of preferably non-circular configuration and carries a sheet-feeding arm 145 splined thereon at one end and having a sheet-feeding pad 147 at its other end in position to engage the uppermost sheet in the stack on the carrier 25, during the forward movement of the rod 135 toward the roller 17. The arm 145 may be shifted along the rod 135 in order to locate the arm in any desired position so as to accommodate sheets of various width in the carrier 25. The arm may be adjusted along the rod 135 by means of the holding screw 149. The carrier 25 comprises a plate 151, which is vertically shiftable in the frame 15 and which carries an adjustable end plate 153 for abutting the outer ends of the sheets on the carrier whereby to hold the opposite ends of the sheets in abutting relationship with a stop 155 formed in the frame 15 immediately in front of the roller 17 and the pressure roller 23. The plate 151 also carries holding members 157 on opposite sides of the plate 151 faced with a suitable resilient material 159, which may be and preferably is sponge rubber, the members 157 being adjustably mounted on the plate 151 in position to engage the opposite side edges of the sheets resting on the platform in or-

der to retain the under sheets on the carrier as the uppermost sheet 161 is being delivered between the rollers 17 and 23 during the forward movement of the feeding pad 147.

5 As the sheets are delivered successively by the pad 147 between the rollers 17 and 23, it is desirable to elevate the platform 151 and this is accomplished by mechanism including extensions 163 formed as lugs fastened to and extending downwardly of the plate 161. The lugs 163 are formed with racks 165 in position to engage pinions 167 drivingly connected with a shaft 169, which is journaled in the frame 115 and which carries a gear 171 in position to drivingly engage a pinion 173 carried on a shaft 175.

The shaft 175 is journaled in the frame 15 and carries an easily accessible handle 177 whereby the elevating mechanism may be manually controlled by the operator of the printing apparatus. The shaft 175 also carries a ratchet wheel 179 and one of the levers 137 carries a pawl 181 in position to engage the ratchet wheel 179, the pawl being connected by means of the rod 183 with an arm 185 fixed on the rod 135 and adapted to be moved in response to the tilting movement imparted by the connecting rod 133.

10 As the sheets are successively delivered between the rollers 17 and 23, the elevation of the feeding pad 147 with respect to the frame 30 will drop, which will cause the rod 135 to tilt more and more in a clockwise direction about its axis and will thus control the pawl 181 through the rod 183 in order to actuate the ratchet wheel and drive the carrier elevating mechanism in a direction to raise the carrier and maintain the uppermost sheet of the stack in the carrier at a proper elevation for feeding to the printing roller.

A suitable sheet counting device 185 may be 40 mounted on the frame 15 in position to count the printed sheets as the same are delivered from between the rollers 17 and 23 into the receiver 29 and a handle 187, in geared relationship with the shaft 165, may be provided for 45 manually turning the drum 17 independently of the motor 19. The device 15 may also be mounted on a supporting base 189 provided with drawers 191 having handles 193 for the storage of stencils, printing paper, and tools necessary 50 in connection with the use of the apparatus.

The drum 17 may, of course, be made in any suitable or preferred manner in order to provide for the reception of the printing form or stencil and to illustrate my invention, I have 55 shown a drum comprising a central stencil-carrying portion 31 and end plates 33. The central stencil-carrying portion is preferably formed of any suitable insulating material and is provided with an internal chamber adapted to contain moisture, means being provided to permit the escape of moisture at the peripheral portions of the drum to afford a current path for the return of electrical currents from the cut portions of the stencil during the printing operation. To 60 this end, the central portion of the drum is preferably formed of Bakelite or other suitable moldable material formed as an open ended casing, the walls of which comprise a partially cylindrical portion 35 and a flat or plane portion 37, the cylindrical portion being provided with a multiplicity of spaced apart perforations 39 through which a limited amount of moisture may escape from the interior of the drum behind the stencil which is mounted on the outer curved 65 surface of the drum.

I find it desirable to limit the amount of moisture which is permitted to accumulate behind the stencil and to this end the interior of the drum is filled with any suitable absorbent material 41, which is kept moist by dripage from a reservoir 43 mounted in the drum. The reservoir may be filled with a supply of moisture from time to time by the operator of the machine. The liquid escapes from the reservoir through relatively small openings 45 into a central fluid distributing compartment 47 formed within the stencil-carrying drum by means of a partition 49, containing perforations 51, through which the moisture, delivered into the distributing compartment 47, may escape into a chamber 53, which contains the absorbent material 41 and which is disposed between the partition 49 and the outer wall 35 of the drum. Partitions 55 are also preferably formed within the fluid distributing chamber 47 in order to assist in the fluid distributing function and also to add strength to the element 31. The central portion 31 of the drum and the end plates 33 may be secured together in any suitable or preferred manner and preferably by means of the studs 51, which hold the end plates in position to close the open ends of the central drum-like element 31.

The drum portion 31 is provided with flanges 59, 61, the same comprising extensions of the curved wall 35 and these flanges contain a plurality of spaced studs 63 adapted to receive the eyelets 113 at the opposite ends of the stencil in order to support the same in stretched position on the outer curved surface of the wall 35. The studs on one flange are preferably of electrical conducting material adapted to form electrical contact with the eyelets at one end of the stencil and the studs on at least one flange are shiftably mounted and normally spring-pressed in a direction to tighten the stencil upon the wall 35, said shiftable studs being depressible to facilitate mounting the eyelets at one end of the stencil thereon. The drum 17 is mounted upon a shaft for rotation therewith, the mounting being accomplished by securing the end plates 33 upon the shaft, the shaft extending through the compartment 47 in the interior of the element 31. The shaft 65 carries slip rings 67 and 69, which have wiping contact with sliding terminals or brushes 71 and 73 stationarily mounted on the frame 15, which are connected in an electrical circuit, including a suitable power source and control means as indicated in Figure 6 of the drawings. Power from the external source may be delivered to the system through a plug-in connection 193 comprising a pair of conductors 195 and 197 between which a condenser 199 is connected for the purpose of preserving the current applied between the conductors as uniform as possible. One of the conductors 197 is connected in series with a pilot lamp 201, a printing control switch 203 and thence to the brush 73, the other brush 71 being connected through a control resistance 205 to the conductor 195 thus completing the printing circuit. The motor also may have a power supply conductor including a control switch 207 connected to the conductor 195 and a return conductor connected through a starting control 209 to the conductor 197. The switches 203 and 207 and the controls 205 and 209 may be mounted in readily accessible position on the frame 15.

One of the slip rings is connected by means of a conductor 15 to the electrical conducting studs 75

63 on the flange 59 whereby to form a direct electrical connection with the conducting layer 103 of a stencil mounted on the drum, while the other slip ring is connected by means of the conductor 17 to form a return connection from the perforated portions of the stencil, said return connection being in part through the fluid medium applied behind the stencil from the reservoir 43. In order to most conveniently accomplish the return connection, the outer surface of the wall 35 carries a plate 79 of electrical conducting material, which is provided with a multitude of minute perforations 85 to permit the passage of liquid which escapes from the chamber 53 through the larger perforations 39. The plate 79 is preferably permanently fastened to the outer surfaces of the wall 35 by means of fastening members 81, which connect the opposite ends of the plate 79 to the flanges 59 and 61, said plate 79 being electrically connected with the conductor 17. I prefer to apply the plate 79 to the outer surfaces of the curved wall 35, since I thus am able to utilize the plate in distributing the current-carrying moisture uniformly behind the stencil although it is obvious that the plate 79 might be arranged in any position on the drum, providing it is in contact with the current-carrying moisture in order to provide a return circuit for the electrical printing currents. I contemplate also the provision of a relatively thin fibrous layer 83 on the outer surface of the current-carrying plate 79 in order to provide a still more uniform distribution of the moisture over the inner surface of the stencil when the same is mounted on the drum, the outer surface of the wall 35, which is in contact with the plate 79, also may be provided with shallow grooves in order to facilitate the passage of the moisture from the perforations 39 to the minute perforations 85 of the plate 79 to thus aid in the uniform distribution of the current-carrying liquid behind the stencil.

Referring now more particularly to Figures 7 and 8, which illustrate various modes of employing the principles of my present invention in electrical printing:

The invention may be practiced by treating the sheet, upon which the printing is made, with a suitable preferably colorless chemical adapted to turn color when exposed to the electrolytic action of currents applied to the sheet in accordance with a desired design as by means of the stencil 101, in which the design has been previously cut. To this end, I may utilize potassium iodide starch paper, that is to say, material treated with potassium iodide, which is colorless but which, when contacted with an electrically charged electrolyte, produces in a dark brown precipitation of iodine at the exposed portions. Other chemicals may be employed to provide pigmentation of different colors and I may even employ a plurality of chemicals such as potassium chloride and phenolphthalein, in the sheet in order to accomplish multi-color printing, the chemicals employed being selected in accordance with the strength of current and the time required to accomplish precipitation so that by applying current of a certain strength one of the chemicals in the paper may be reacted in order to precipitate pigment of a desired color while another pigment in the paper remains inactive, or substantially so, and by increasing the strength of the applied electrical currents both chemicals may be reacted to precipitate pigment having a combined color different from that

produced by reacting one chemical only. Potassium chloride, a normally colorless material, turns brown when exposed to the action of an electrified or electrically charged electrolyte, while normally colorless phenolphthalein turns red if similarly treated. The change in color effect takes place at unlike rates of speed, varying to some extent in accordance with the concentration of the chemical in the element being printed. The rate of color development varies as a function of the density of the current employed in electrifying the electrolyte. If, therefore, an element to be printed contains colorless potassium chloride and phenolphthalein in suitable proportions, the element may be printed red by exposing it to an electrolyte carrying a predetermined current density and may be printed a brownish color by exposing it to an electrolyte-carrying current of greater density. Selection of other reactive substances affords the possibility of printing any desired combination of colors.

In practicing this process, the metallic layer 103 of the stencil, as well as the plate 79, are preferably formed of current-carrying material, such as aluminum, which is substantially inert to electrolytic action and printing may be accomplished by applying either alternating current or direct current between the stencil and the plate 79.

The process may also be practiced, without previously treating the sheets to be printed, by forming the metallic layer 103 of the stencil, or the plate 79, of suitable, preferably metallic material capable of being deposited by electrolytic action, for instance, silver may be deposited electrolytically as a black pigment, iron as a red pigment, copper as a green pigment, upon the sheet in accordance with a desired design cut in the stencil 101.

In practicing the process wherein a compound of the material of the stencil or of the element 79 is deposited on the sheet being printed, it is desirable to utilize direct current only and to apply the direct current potential as shown in Figure 8 between the plate 79 and the metallic layer of the stencil. If the polarity of the applied electrical potential is such that current flows through the layer 83, which, it will be remembered, is saturated with a suitable current-carrying liquid electrolyte drawn from the reservoir 43 through the distributing chambers 47 and 53, and thence through the perforations 39 and 85, from the plate 79 to the layer 103 of the stencil, as shown in Figure 8, it will deposit a compound of the material of which the plate 79 is formed.

The current-carrying electrolyte may pass the insulating layer only at the places where the same has been perforated in cutting the stencil and the electrified electrolyte may enter the depressions or openings formed in the metallic layer of the stencil, it being remembered that the moisture contained in the layer 83 will be squeezed into the perforations of the stencil at the time when the perforations come opposite the backing roller 23, thus permitting the current-carrying electrolyte to enter the perforations of the stencil at the instant when the sheet, being printed, is opposite such perforation. The electrically active electrolyte is thus disposed in the perforations in position to contact the surface to be printed, and, I have found, creates pigmentation in the surface of the sheet exposed opposite the perforations. The current may return to the power source through the layer 103, the eyelets 113, the studs 63. By reversing the

5 polarity of the applied direct current electrical potential, as shown in Figure 9, the current may be caused to flow from the layer 103 through the electrolyte in the cut impressions of the stencil 10 at the instant when the same are pressed against the sheet being printed by the backing roller. These electrical currents liberate, in ionic form, the compound derived from the layer 103, thereby permitting a deposit of the compound on the 10 surface of the sheet being printed. The current may return to the source by way of the current-carrying electrolyte, which has been squeezed into the perforation from the layer 83. I find that no matter in which direction the current 15 flows in the perforations, pigment is developed on the sheet being printed at and near the edges of the perforations. This will have no appreciable effect in a printed character comprising a thin line but where the perforation is of appreciable 20 breadth, as where an oval opening is punched through the stencil, the pigment will appear at the edges of the oval perforation, leaving the central portions unprinted. It is possible, therefore, to obtain an accurately printed letter, such 25 as an "o", by punching entirely through the stencil without making any provision as is ordinarily necessary for the blocking of the printing effect in the central area of the character. This 30 effect is present also in the process requiring chemically pre-treated sheets as well as in the process where the pigment is derived from the stencil and is an important feature of the invention.

It will be noted that the electrical currents 35 utilized in printing, in accordance with the teachings of my present invention, are applied in such a way that they do not pass entirely through the printed sheet but the current carrying electrolyte is applied to one side of the sheet 40 only. It is thus not necessary to moisten the sheet in order to permit current flow entirely through the sheet. The resultant printing is sharply defined and kept within the confines of the 45 perforations formed in the stencil.

45 By employing electricity in order to print and by utilizing a stencil characterized by the absence of any free pigment, I have produced a printing process which is clean and neat and will not soil the hands or clothes of the operator 50 who cuts the stencil or the operator who produces the copies. By eliminating the necessity of moistening the sheet, I am able to produce accurate prints without distortion through stretching or warping of the sheet. By eliminating the necessity of passing the electrical 55 printing currents through the sheet, I am able to print on sheets of any desired thickness, on wall surfaces and the surfaces of other solid objects by suitably revising the printing machine.

60 My new electrical printing process may be accomplished by means of apparatus of exceedingly simple inexpensive character, which is entirely automatic and in which the speed of printing is governed solely by the maximum operating speed of the apparatus employed. By utilizing different metals in the plate 79 and in the stencil, or by employing a plurality of chemicals in the pre-treated sheet, I am able to change the color of the characters at will.

65 Numerous other objects, advantages, and inherent functions of the invention will be apparent from the foregoing description and it is obvious that numerous changes may be made in the form, construction, and arrangement of the several parts without departing from the spirit

or scope of my invention or sacrificing any of its attendant advantages; the forms herein described being preferred embodiments for the purpose of illustrating my invention.

Having thus described my invention, what I claim as new and desire to secure by Letters Patent is as follows:

1. Printing apparatus comprising a mounting for a printing form, means comprising studs on said mounting formed for interlocking engagement with the form to secure the same on said mounting in printing position, said studs having means adapted to form an electrical connection with said form when the same is mounted on the studs, and means to electrically connect the studs in an electrical circuit.

2. A method of printing on relatively dry material which comprises bringing into contact with the dry material through a printing stencil an aqueous liquid medium containing an electrolyte and adapted to carry current, passing a current through said electrolyte between electrodes, both of which are located on one side of the dry material and at least one of which is associated with the stencil in close proximity to the dry material and in contact with the electrolyte.

3. A method of printing on relatively dry material which comprises bringing into contact with the dry material through a printing stencil an aqueous medium containing an electrolyte which is also in contact with a pair of electrodes located on the same side of the dry material, at least one of the electrodes being disposed within the stencil in close proximity to the dry material and while the aqueous medium is so in contact with the electrodes and dry material, applying a source of electric current having a substantial electromotive force to said electrodes.

4. The method of printing which comprises bringing into contact with the surface to be printed a printing stencil having apertures therein, supplying at said apertures an aqueous liquid medium containing an electrolyte adapted to carry current, and passing electric current from an electrode exposed at the margin of said aperture and in relatively close adjacency to the surface to be printed to a second electrode on the same side of said surface to be printed.

5. Printing apparatus comprising a printing stencil having an insulated work contacting surface, printing recesses provided in said surface, electrode means disposed within said recesses and in relatively close adjacency to said work contacting surface, means for delivering an aqueous current-carrying liquid medium containing an electrolyte through said recesses, means for contacting said insulated surface and said current-carrying liquid with a work surface to be printed, and a second electrode means disposed on the same side of the work contacting surface and operative to coact with said first named electrode means and means to pass a current of electricity through said current-carrying liquid.

6. A printing form for use in printing according to the method of claim 2 comprising a laminated stencil including a current-carrying layer, a strengthening layer and an electrically insulating layer, said electrically insulating layer being relatively thin whereby said current-carrying layer resides relatively closely to the surface of said printing form and in close proximity to a work surface when in printing relation thereto.

7. A printing form for use in printing according to the method of claim 2 comprising a laminated stencil including a current-carrying layer,

a layer of fibrous material adjacent the current-carrying layer, and layers of waterproof insulating material on the outwardly facing surfaces of said current-carrying and fibrous layers, said insulating layer on the outwardly facing surface of said current-carrying layer being relatively thin whereby said current-carrying layer resides relatively closely to the surface of said printing form and in close proximity to a work surface when in printing relation thereto.

8. Printing apparatus comprising a main roller, means to rotate said main roller, a pressure roller in position to present a sheet to be printed against said main roller, means carried by said main roller comprising a printing stencil upon a surface of said main roller and including means formed and arranged on said main roller to deliver an aqueous current-carrying fluid medium containing an electrolyte behind the printing stencil when mounted, said means carried by the main roller also comprising a pair of electrodes, both on the same side of the sheet to be printed, at least one of said electrodes being disposed near the outer surface of the stencil for contact with the electrolyte and in relatively close adjacency to said sheet when the sheet is arranged in operative relation, and means for passing current through the electrolyte by means of the electrodes.

9. Printing apparatus comprising a mounting for a printing stencil, means to secure a stencil on said mounting, and means formed and arranged in said mounting to deliver an aqueous current-carrying medium comprising an electrolyte behind said mounted stencil, an electrode formed in said stencil in contact with the electrolyte and second spaced electrode means on the same side of the printing surface of the stencil, and means to pass current through the electrolyte by means of the electrodes.

10. Printing apparatus comprising a printing stencil, means on the rear side of the plane of the printing surface of said stencil including an electrode to deliver an aqueous liquid current-carrying medium containing an electrolyte through the openings in said stencil into contact with the surface to be printed, said stencil including cooperative electrode means disposed adjacent the margins of said openings and means for passing current through the electrolyte by means of the electrodes.

11. Printing apparatus comprising a printing stencil, means on the rear side of the plane of the printing surface of said stencil including an electrode to deliver an aqueous liquid current-carrying medium containing an electrolyte through the openings in said stencil into contact with the surface to be printed, said stencil including electrode means disposed therein but exposed at the margins of said openings, and means for passing current through the electrolyte by means of the electrodes.

12. A printing form for use in printing according to the method of claim 2 comprising a laminated stencil including a current carrying layer, a strengthening layer, and a pair of electrically insulating layers, said strengthening layer being located between said current carrying layer and one said insulating layer, said other insulating layer being located on the work contacting side of the stencil and being relatively thin whereby said current carrying layer resides relatively closely to the surface of said printing form and in close proximity to a work surface when in printing relation thereto.

13. Printing apparatus comprising a laminated printing stencil, including a current carrying layer, a strengthening layer and an electrically insulating layer, said stencil having a work contacting surface and said insulating layer being located adjacent an opposite surface for insulating the rear surface of the stencil, printing recesses provided in said stencil, said current carrying layer presenting edge portions at said recesses providing electrode means disposed within said recesses in relatively close adjacency to said work contacting surface, means for delivering an aqueous current carrying liquid medium containing an electrolyte through said recess, means for contacting said work contacting surface and said current carrying liquid with a work surface to be printed, and a second electrode means disposed on the same side of the work contacting surface and operative to coat with said first named electrode means, and means to pass a current of electricity through said current carrying liquid.

14. A printing form for use in printing accord-

ing to the method of claim 2 comprising a laminated stencil including a current carrying layer, a strengthening layer, and a pair of electrically insulating layers, one insulating layer being disposed on the outwardly facing surface of said current carrying layer and being relatively thin whereby said current carrying layer resides relatively closely to the surface of said printing form and in close proximity to a work surface when in printing relation thereto, the other insulating layer being located on the inwardly facing side of the current carrying layer and separated therefrom by the strengthening layer.

15. A printing form for use in printing according to the method of claim 2 comprising a laminated stencil including a current carrying layer, a strengthening layer, and an electrically insulating layer, the insulating layer being located on the inwardly facing side of the current carrying layer and separated therefrom by the strengthening layer.

JAMES K. DUNCAN.
